UNITED STATES PATENT OFFICE.

JOHN GRIFFIN, OF CORK, IRELAND.

METHOD OF MANUFACTURING FLAT WOVEN GUT BELTING.

SPECIFICATION forming part of Letters Patent No. 429,270, dated June 3, 1890.

Application filed January 13, 1890. Serial No. 336,830. (No model.) Patented in England April 9, 1889, No. 6,039.

To all whom it may concern:

Be it known that I, JOHN GRIFFIN, machine-band manufacturer, of Cork, in the county of Cork, Ireland, a citizen of the United Kingdom of Great Britain and Ireland, have invented a certain new and Improved Method of Manufacturing Flat Woven Gut Belting, (for which I have obtained Letters Patent in Great Britain, No. 6,039, dated April 9, 1889;) and I do hereby declare that the following is a full, clear, and exact description thereof.

This invention has reference to improvements in the manufacture of gut belting, whereby I am enabled to produce belts or bands of this material of sufficient width and length for use in connection with flat pulleys or wheels.

In carrying out my invention I prepare, in the first instance, suitable strands of gut by spinning on a wheel in the ordinary way; and I then take several of these strands, according to the thickness and strength of the belt to be made, and spin them into one string or thread. The strands, strings, or threads thus prepared are then strained and softened in water or oil until they are soft enough to weave close, when a sufficient number, according to the width of belt to be produced, is placed in the loom and woven as close as pos-

sible by twilling, (or tweeling,) or in any other suitable way found convenient. When the weaving process is completed, the fabric is taken from the loom and dried, when it is ready for use.

Cotton, linen, jute, or other ordinary material may serve as the filling or weft.

Having thus described the nature of my said invention, I would have it understood that what I claim is—

The improved method of manufacturing flat woven gut belting, which consists in first spinning gut into threads, then twisting together several of these threads into a compound strand, then straining the strands thus formed and softening the same in water or oil, and finally weaving them as warp into a fabric suitable for belting, substantially as described.

In testimony that I claim the foregoing I have hereunto set my hand this 23d day of July, 1889.

JOHN GRIFFIN.
